Primary Examiner — Daniel Bui(74) *Attorney, Agent, or Firm* — Keusey & Associates, P.C.(57) **CLAIM**

The ornamental design for a male electrical connector, as shown and described.

DESCRIPTION

FIG. 1 is a top, front and left side perspective view of a male electrical connector in an unlocked position, showing my new design.

FIG. 2 is a right side elevational view thereof, the left side being a mirror image thereof.

FIG. 3 is a front side elevational view thereof.

FIG. 4 is a back side elevational view thereof.

FIG. 5 is a top plan view thereof.

FIG. 6 is a bottom plan view thereof; and,

FIG. 7 is another right side elevational view thereof, in a locked position. The broken line therein represents an unlocked position.

The broken lines in the drawing views represent unclaimed environment only, and form no part of the claimed design.
